UNITED STATES PATENT OFFICE.

HARRY G. AINSWORTH, OF KENTLAND, INDIANA.

APPARATUS FOR OPERATING HINGED DOORS.

Application filed March 24, 1924. Serial No. 701,612.

This invention relates to electrically operated devices for opening and closing hinged doors and consists in the devices and combinations of devices herein illustrated described and claimed.

The principal object of the invention is to provide an apparatus which will include an operating motor, means to stop the motor at a particular time and simultaneously reverse the motor field, so that when again set in motion, the motor shaft will travel in the opposite direction. Thus, the operator, to open a closed door, will simply push an operating switch to throw on the current, and the apparatus will open the door, and he will merely push the same switch to cause the apparatus to close the door. This object and the advantages of my invention will be more manifest as I proceed with my specification.

In the accompanying drawings:

Fig. 1 illustrates in elevation, a pair of hinged doors to which the apparatus of my invention has been applied, one on each door.

Fig. 2 is a vertical, sectional view, enlarged, of a portion of the apparatus, the section being taken in the plane of the dotted line 2-2 shown on Fig. 3.

Fig. 3 is a horizontal, sectional view, also enlarged, of the housing attached to the door, showing the motor and connected parts in plan view, the section being taken in the plane of the dotted line 3-3 shown on Fig. 2.

Fig. 4 is a fragmentary side view of the cam arrangement employed in the apparatus.

Fig. 5 is a plan view of the apparatus, showing the attachment to the door and the fixed support, the latter being in section.

Fig. 6 is a side view of the same with the door and support in vertical section, the section being in the plane of the dotted line 6-6 shown on Fig. 5.

Fig. 7 is a bottom view, partly in section, of one of the swinging arms, looking upward in the plane indicated by the dotted line 7-7 on Fig. 6.

Fig. 8 is a diagrammatic view of an electric circuit for operating the device.

In that form in which I have illustrated my invention, A, A' are doors closing a suitable opening in a fixed support B, and C, C' are the side members of the door frame to which the doors are hinged at a, a'. D, D', are housings secured to the doors by bolts 1 or other suitable means, within and to which nearly all of the operating parts are

mounted. E designates the electric circuit as a whole.

Within the housing D is a motor M which will rotate its shaft in one direction until its field is reversed and will then rotate its shaft in the opposite direction. As the motor M may be of standard conventional type, and per se constitutes no part of my invention except as a unit, no further description of the same is required.

The motor shaft 2 carries on its extended end a worm 3 in mesh with a worm gear 4 on a shaft 5, vertically and rotatively journalled in the housing D. Upon the upper extended end of this shaft 5 is an arm 6, the outer end of which is pivotally connected with the swinging end of another arm 7. This arm 7 is pivotally mounted to a bracket 8 secured to the support B.

The location of the bracket 8 with relation to the location of the housing D on the door will be such that when the motor rotates the shaft 5, the arm 6 will swing to the right or left as the case may be, and in turn swing the arm 7 in the same direction, and since one end of the arm 7 is pivotally secured through its bracket 8 to the fixed support, it follows that the door will swing on its hinges to open or to close, as the case may be.

The housing D is provided with a flange bearing 9 on an integral bracket 10, on which bracket are mounted two switches 11 and 12 which are in the motor circuit E.

These switches have projecting operating knobs or buttons 13 and 14 respectively. A slideable bar 15 is provided with an elongated slotted portion 16 at one end where it surrounds and has bearing upon a cylindrical projection 18 of the housing. The other end 17 is mounted in the flange bearing 9 of bracket 10. Intermediate the portions 16 and 17 this slideable bar 15 is provided with two apertures 19 and 20 to engage the switch knobs 13 and 14 respectively. Thus when the bar 15 is moved in one direction, say to the right, the switch knobs 13 and 14 are simultaneously moved in the same direction, and the latter are moved to the left when the bar 15 is moved to the left.

The bar 15 is provided with two spaced apart, downwardly projecting arms 21 and 22 carrying inwardly directed adjusting screws 23 and 24 respectively. The shaft 5 projects downwardly through the cylindrical portion 17 of the housing and carries upon said projecting portion two cams 25

and 26. The cam 25 is in the same horizontal plane as the screw 24, the end of which rests against the face of the cam. The cam 26 is in a lower plane so that its face will bear against the end of the screw 23. The cams are so positioned on the shaft 5 and so adjusted by the screws 23 and 24 with relation to the arms 21 and 22, that one cam will move the slidable bar 15 to the right 10 and the other cam move said bar to the left.

Referring to the circuit E of Fig. 8, the line contains two or more operating switches S, R, placed at locations convenient for the persons who may desire to operate my device to open or close the doors A, A'. One line α runs direct to the motors M. The other line through switches S, R, to the switches 12 of each device by the lines X and Y. Thus switches S, R and 12 open 15 and close the circuit while switches 11, as before stated, operate to reverse the field of the motor; switches 11 and 12 being simultaneously actuated by the bar 15.

If, when the door is in process of being 20 swung on its hinges, either to open or to close the same, any unusual jar should occur, such as the door being struck by a moving vehicle, injury might occur to the operating device. To guard against this, I 25 provide a buffer arrangement between the housing and the arm 6. By referring to Fig. 7, it will be seen that the arm 6 is provided on its under side with a pair of apertured lugs 27, 27, the apertures of which act as bearings for a slidable bolt member 28. Surrounding the bolt is a spring 29, one end of which bears upon the inner surface of one of the lugs 27 and the other end against a nut or collar 30. Immediately below the arm 6 is a disc or collar 31 which is keyed upon the shaft 5. At one point in its periphery, this disc is provided with a notch 32, the sides of which flare so as to form in effect a cam surface. In the normal position 30 of the device, the end of the bolt 28 will rest in this cam notch 32. The tension of the spring 29 is such that, notwithstanding the fact that the arm 6 is loosely mounted upon the shaft 5, the rotation of said shaft 5 carrying with it the fixed cam disc 31, will, through said bolt 28, swing the arm 6 in the proper direction, as hereinbefore described. On the other hand, in the event of any sudden jar to the door, there will be obtained a certain amount of yield, or lost motion, or relative movement between the shaft 5 and the arm 6, by reason of the fact that in the rotation of the shaft 5 and disc 31, the end of the bolt 28 will instantly ride over the cam surface of the notch 32 and rest upon the concentric margin of the disc 31. The spring 29 is sufficiently compressed for this purpose by reason of the suddenness of the jar. Any further rotation of the shaft 5 will result in the spring forcing the bolt

28 into the notch 32 and thus again lock the arm 6 to the shaft 5.

I claim as my invention:

1. An apparatus for operating hinged doors comprising an arm pivotally secured 70 at one end to a fixed support, a hinged door, a reversible electric motor on the door, a second arm one end of which is pivotally connected to the swingable end of said first mentioned arm, operative connections between the motor and said second arm for actuating the latter, an electric circuit provided with a motor reversing switch and a controlling switch, and means for simultaneously operating both switches. 80.

2. An apparatus for operating hinged doors comprising an arm pivotally secured at one end to a fixed support, a hinged door, a reversible electric motor on the door, a rotatable shaft operatively connected with said 85 motor, a second arm mounted at one end upon said shaft and pivotally connected to the swingable end of said first mentioned arm, an electric circuit provided with a motor reversing switch and a controlling switch, 90 and means operatively connected with said shaft for simultaneously operating both switches.

3. An apparatus for operating hinged doors comprising an arm pivotally secured 95 at one end to a fixed support, a hinged door, a reversible electric motor on the door, a rotatable shaft operatively connected with the motor, a second arm mounted on said shaft and pivotally connected at one end to the 100 swingable end of said first mentioned arm, an electric circuit provided with a motor reversing switch and a controlling switch, and means for simultaneously operating both switches, said means including a movable 105 arm operatively connected with each switch, lugs on said arm and cams on said shaft adapted to contact with the lugs.

4. In an apparatus for operating hinged doors, a hinged door, a housing mounted on 110 the door, a rotatable shaft therein, a reversing motor in said housing operatively connected to actuate said shaft, an electric circuit, a reversing switch and an operating switch in the circuit located adjacent the 115 motor, and operative connections between the shaft and said switches for simultaneously and automatically operating both switches.

5. In an apparatus for operating hinged doors, a housing mounted on the door, a rotatable shaft therein, a reversing motor associated with the housing operatively connected to rotate said shaft, an electric circuit, a reversing switch and an operating 125 switch in the circuit located adjacent the motor, and operative connections between the shaft and said switches for simultaneously and automatically operating both switches, said switch operating connections 130

including a slidable bar, cams on said rotatable shaft, opposed lugs on the bar, and means on the shaft for alternately engaging said lugs to actuate said bar.

5. 6. In an apparatus for operating hinged doors, a housing mounted on the door, a rotatable shaft therein, a reversing motor associated with the housing operatively connected to rotate said shaft, an electric circuit, a reversing switch and an operating switch in the circuit located adjacent the motor, a slidable bar operatively connected with said switches, spaced apart lugs on said bar, cams mounted upon said shaft in different planes and intermediate said lugs and adjustable means on each lug positioned in the path of rotation of its proper cam to be contacted thereby.
7. An apparatus for operating hinged doors comprising an arm pivotally secured at one end to a fixed support, an electric motor on the door, a second arm one end of which is pivotally connected to the swingable end of said first mentioned arm, means 20 for communicating motion from the motor to the second arm, including a shaft on which said second arm is loosely mounted,

yielding locking connection between said arm and shaft, an electric circuit provided with a motor reversing switch and a controlling switch and means for simultaneously operating both switches. 30

8. An apparatus for operating hinged doors comprising an arm pivotally secured at one end to a fixed support, an electric motor on the door, a second arm one end of which is pivotally connected to the swingable end of said first mentioned arm, means for communicating motion from the motor to said second arm, comprising a rotatable shaft on which said second arm is loosely mounted, a notched disc fixedly mounted on the shaft, a yielding locking bolt on said second arm and engaged, normally, in said notch, and gearing connecting said shaft and the motor shaft, an electric circuit provided with a motor reversing switch and a controlling switch, and means for simultaneously operating both switches. 35 40 45

In testimony that I claim the foregoing as my invention I affix my signature this 18th 50 day of March, 1924.

HARRY G. AINSWORTH.
